UNITED STATES PATENT OFFICE.

HALLIE E. TRIPP, OF CHATTANOOGA, TENNESSEE.

ADJUSTABLE WEATHER STRIP AND STOP FOR CLOSURE MEMBERS.

Application filed April 18, 1921. Serial No. 462,077.

To all whom it may concern:

Be it known that I, HALLIE E. TRIPP, a citizen of the United States, residing at Chattanooga, in the county of Hamilton and State of Tennessee, have invented certain new and useful Improvements in Adjustable Weather Strips and Stops for Closure Members, of which the following is a specification.

10 This invention relates to an adjustable weather strip and stop for use upon closure members, such as doors, windows and the like.

The primary object of the invention is 15 the provision of an adjustable weather strip for use upon doors and the like, which will be automatically extended upon closing of the door, to engage a floor or other surface, thus doing away with threshold projections, 20 and providing a sealing of all cracks or crevices incident to ordinary door construction.

A further object of the invention is the 25 provision of an adjustable weather strip of the above described character, which includes means for extending the weather strip into engagement with a floor surface at any open or closed position of the door, thus acting as a stop to maintain the door 30 in any predetermined position.

A further object of the invention is the 35 provision of an automatic weather strip which is simple and practical in that the same can be evenly forced into engagement with a floor surface throughout its length without buckling, and thus prevent any undue wear upon any one part to the exclusion of others.

A further object of the invention is the 40 provision of an automatic weather strip of the above described character and use, which can be built into doors as a unit part thereof; or can be sold as an accessory for attachment to any type of door of standard construction.

Other objects and advantages will be apparent during the course of the following detailed description.

In the accompanying drawings, forming 50 a part of this specification, and in which similar reference characters designate corresponding parts throughout the several views,

Figure 1 is a side elevation, partly in 55 cross section, of the improved automatic

weather strip, showing the application of the same to a closure member, such as a door.

Figure 2 is a horizontal cross sectional view through the improved automatic 60 weather strip.

Figure 3 is a side elevation of the improved automatic weather strip showing the same attached to a door in closed position, so that the weather strip is extended 65 into engagement with a floor surface.

Figure 4 is a vertical cross sectional view through the improved device, showing the preferred arrangement adapted for use as an accessory upon any type of closure 70 member.

Figure 5 is a vertical cross sectional view showing the improved automatic weather strip built into the door and in a less conspicuous place than the accessory form illustrated in Figure 4. 75

Figure 6 is a side elevation of a detail of the invention.

Figure 7 is a perspective view of a detail used in extending the improved weather 80 strip.

Figure 8 is a perspective view of a detail of this invention.

In the drawings, wherein for the purpose of illustration is shown the preferred embodiment of my invention, the letter A designates a door or other closure member, which is hingedly connected to a door jamb or other support B, as by hinge C. In the form of this invention adapted for use as 90 an accessory upon doors, the casing D is adapted for detachable positioning upon the lower edge of the door and adjustably supports the flexible weather strip E through resilient means F. Automatic adjustable 95 means G is provided for operation of the resilient means F to extend the flexible strip E into engagement with a floor surface H; and which means G is normally maintained in position to keep the flexible 100 means E off of the floor surface H, as by the independent spring means K. An adjustable means L is provided for manual operation to extend the flexible weather strip into engagement with the floor surface 105 H at any open or closed position of the closure member A, with respect to the support B.

The closure member A as before mentioned, may be of any preferred type and 110

the bottom end 10 thereof is normally raised from the floor surface H as illustrated in Figure 1, and as is generally the case in ordinary door construction; said space being sealed when the door is closed by a threshold projecting upwardly from the floor surface H in ordinary construction.

The housing D is preferably of the same length as the width of door A and provided 10 with an upstanding flange 15 for the reception of screws 16 or the like for detachably positioning the same exteriorly upon the door A. A projecting cover 17 is bent at right angles to the flange 15, and is provided 15 with a downwardly projecting front cover 18, substantially at right angles thereto in order to provide an enclosure or recess 19 for the reception of the working elements and details of the improved automatic weather strip. One end of the housing D, which is 20 positioned adjacent the free end of the closure member A, is normally sealed by a flanged over portion 20; while the other end 21 is provided with an opening 22 therein, 25 a portion of the end 21 being bent inwardly as at 23 and rounded upon its extremity; and which aperture 22 is provided to permit reciprocation of a portion of the operating means, and which will be subsequently set 30 forth.

The flexible weather strip E may be of any approved material, such as rubber, oil treated fiber, or the like, and is preferably 35 rectangular in formation, and provided with longitudinal recesses 25 upon each side thereof and extended the full length of said strip. A holder 27 substantially U-shaped in cross section is provided, for disposition upon the top of the flexible weather strip 40 and is provided with inturned ends 28 upon the depending arms thereof, for firm engagement within the recesses 25 upon each side of the weather strip E. In this manner 45 the weather strip is reinforced upon its top by means of more substantial material than that which composes the weather strip itself, and which is necessary for cooperation with the other elements. The top or bight portion 29 of the holder 27 is provided at 50 spaced intervals with suitable screw threaded apertures for the reception of detachable screws 30 or the like.

The resilient connecting means F, includes the substantially U-shaped spring members 55 31, which are placed at intervals upon the top 29 of the holder 27, and slidably attached thereto by means of the detachable screws 30 inserted into the slots 32, and which slots 32 are punched longitudinally 60 of the bight portions 33 of the springs 31. Each bight portion 33 is relatively long, and supplies the necessary resiliency required of the means F. A leg 34 of each of the members 31 is rigidly attached to the 65 top 17 of the housing D by means of the

angle piece 35. One leg 36 of the angle 35 is rigidly attached to the top 17 by rivets or spot welding, while a depending leg 37 is rigidly attached to the upstanding leg 34 by rivets or the like.

The free upstanding end 40 of each of the U-shaped spring members 31 is riveted or otherwise secured to a pushing lug 41 through a suitable aperture 42 therein. The push lug 41 is in reality part of the operating means G, and each of the push lugs 41 is detachably positioned upon the longitudinal bar 43, by means of the projecting arms 44 and 45. The projecting arm 45 of each of the members 41 is inserted through a suitable aperture transversely in the bar 43, while the under or bottom arm 44 engages beneath the bar 43, thus maintaining the push lugs 41 in position upon the bar 43. The bar 43 is slidably disposed in the recess 19 of the casing D and is positioned upwardly therein adjacent the side portion 18. In order to permit free reciprocation of this bar 43, the various U-shaped springs 31 have their legs 34 and 40 notched as at 47. Likewise the L-shaped members or angles 35 are narrower in width than the width of the recess 19, and are each preferably provided with a projecting end 48 underlying the slide bar 43. The end 49 of the slide bar 43 which is positioned adjacent the hinged end of the closure member A is flanged in L-shaped manner, and provided with a screw threaded aperture therein extending longitudinally of the bar 43, and facing to 100 communicate with the aperture 22 as provided in the casing D.

An adjustable bolt or screw 51 is provided for adjustment within the aperture in the end 49 of the bar 43; and normally projects 105 from the aperture 22 in the end 21 of casing D substantially as illustrated in Figures 1 and 2 of the drawings. The head 52 of screw 51 is preferably knurled and projects outwardly from the extreme end 53 of the closure member A, in order that the same may contact with the projection 54, which is ordinarily formed upon the jamb or support B.

In this manner, as the closure member A 115 is swung to a closed position upon the hinge C, the head 52 contacts with the projecting end 54 of the support B, and pushes back the operating means G; and which will be subsequently described in detail.

The resilient means K which normally maintains the operating means G in position to raise the flexible strip E off of the floor surface H, comprises the spiral spring 55 disposed within a suitable pocket 56, and which pocket 56 is formed intermediate the top 17 of casing D and the bottom extension 57 formed by the L-shaped piece 58 which is riveted or otherwise secured on the closed end of the casing D. This spring 55 is nor- 120 125 130

mally maintained under compression, and contacts with the flanged end 60 of the bar 43, to force the same forwardly in order that the head 52 of the adjustable screw 51 5 may extend beyond the surface 53 of the closure member A, and substantially as illustrated in Figure 2.

The flexible weather strip E is not only adapted to replace a threshold, but may likewise 10 act as a stop for maintaining a door in any predetermined position, whether open or closed. To this end, a foot operated lever 61 has been provided, and which is provided with the pawl tooth 62 thereon, 15 for engagement with any tooth 63 upon a rack structure, which may be formed integral, or otherwise be attached in rigid position upon the casing D. The lever 61 is pivotally mounted upon a detachable screw 20 64, which is positioned upon the lower part of the side 18, and which lever is normally maintained in its outward position against a guide rail 64^a, by means of a spiral spring 65 disposed over the shank of screw 64, and 25 in engagement between the side 18 of housing D and the side of the lever 61. In this position, the tooth 62 is out of engagement with the teeth 63. The manual operating means L is provided to operate the flexible 30 strip E independent of the means G; and to this end a detachable screw 68 has been provided, which engages the bar 43, and extends outwardly from the housing or casing D through a slot 69, in order to allow unimpeded movement of the screw 68 synchronously with the bar 43.

When using the improved automatic weather strip as a unit built into the door or closure structure A, the same is altered 40 very little with respect to details thereof. A recess 70 is formed in the under part of the closure structure A, and substantially as illustrated in Figure 5 of the drawing, to provide for insertion of the various elements. In this type of weather strip, a substantially Z-shaped metal stamping 70^a is used, which is detachably mounted to the under surface 71 of the closure member A, as by screws 72 or the like, and the body 45 portion or side 73 of which stamping simulates the side 18 of the casing D. The flexible weather strip E; the resilient means F; the operating means G; and the independent resilient means K are identical to 50 those above described for the accessory form of this invention; and are all disposed within the recess or pocket 70 formed upon the under surface of the closure member A, and operably attached to the leg 75 overlying 55 the top of the pocket 70. A special bracket 76 is provided for attachment upon the outside of the closure member A, and which is detachably positioned thereon as by screws 77 or the like. The bracket 76 is provided 60 with the guard rail 78, for guiding the pawl 65 lever 79 pivotally mounted upon the detachable screw 80; and which detachable screw 80 receives the spring 81 for normally forcing the pawl lever 79 outwardly, substantially as above described for the pawl 70 61. The bracket 76 is provided with a suitable slot 83 therein, to permit reciprocation of the detachable screw or bolt 84; and which detachable element 84 engages the operating bar 43, of the means G. In all 75 other respects, the lever 79 and bracket structure 76 are similar to the pawl and rack operating means L as above described.

In operation, as the door or closure member A is swung upon the hinge C into a 80 closed position, the head 52 of the adjustable screw 51 contacts with the surface 54 of the support B, and thus forces the bar 43 to slide into the casing D, further compressing the spiral spring 55 into the position substantially as illustrated in Figure 3. During this operation the substantially U-shaped resilient springs 31 are compressed, so that their bight portions 33 are lowered somewhat, and at the same time will have 90 the effect of pushing the flexible strip E down into engagement with the floor surface H. Since there will, of course, be relative movement of the springs 31 upon the holder strip 27, the slots 32 have been 95 provided, and which allow for such relative movement. The flexible means E and holder 27, are of course prevented from moving with the operating means G by reason of the fact that the ends thereof contact 100 against the ends 20 and 21 of the housing D. Upon opening of the door, the spring 55 will automatically push the rod 43 longitudinally into normal position for further 105 automatic operation of the device upon closing of the door. This spring 55 will of course be assisted in return of the operating means G into normal position by the inherent resiliency of the springs 31. Attention is called to the fact that the screw 51 110 is adjustable and can be so adjusted in the screw threaded aperture in the end 49 of the bar 43, that the same will not project from the surface 53 of the closure member A, even when the operating means G is in 115 neutral position.

When it is desired to use the operating means G as a stop for holding the closure member A in any predetermined position, the lever 61 or 79 is depressed by the foot 120 of the operator upon the top of extension 61^a, and rocked upon the pivoted screw 64 or 80, as the case may be, at the same time forcing the screw 68 or 84 which detachably engages the bar 43, rearwardly, and performing the same operation of lowering the flexible member E into engagement with the surface A as above described for the automatic operating means G. In this position, the tooth 62 of the lever 61 can engage 130

any of the teeth 63, and be held in adjusted position for maintaining the door as the user desires. The lever 61 can of course be released manually, and the spring 65 or 81 5 will assist in maintaining the levers 61 or 79 respectively out of engagement with the rack teeth.

Various changes in the shape, size and arrangement of parts may be made to the form 10 of the invention herein shown and described, without departing from the spirit of the invention or the scope of the claims.

I claim:

1. In a device of the class described, the 15 combination with a closure member, of a casing detachably mounted on said closure member, a flexible strip, resilient means connecting said strip to said casing, means for automatic distorting of said resilient means 20 when said closure member is moved in a predetermined direction to force said strip outwardly from said closure member, and means independent of said resilient means for returning the second mentioned means to 25 normal position.

2. In a device of the class described, the 30 combination with a closure member and support, of a support engaging strip, substantially U-shaped springs slidably connected intermediate their ends to said strip, each 35 of said springs having one end rigidly connected to said closure member, sliding means connected to the free ends of said springs, and means for automatically operating said 40 last mentioned means to adjust said strip with respect to said closure member upon movement of the latter in a predetermined direction.

3. In a device of the class described, the 45 combination with a closure member, of a strip, arcuate springs engaging said strip and rigidly connected at one end of each 50 to said closure member, slideable means connected to the other ends of said springs for movement to distort said springs and move said strip with respect to said closure member, and spring means independent of said arcuate springs for normally forcing said strip toward the center of said closure member.

4. In a device of the class described, the 55 combination with a door hingedly connected to a support, of a flexible weather strip, substantially U-shaped springs slidably connected intermediate their ends to said strip, means connecting one end of each of said 60 springs rigidly to the bottom of said door, a slideable bar connected to the other end of each of said springs, an adjustable contact member engaging said bar and adapted for engaging said support upon closing said door to distort said springs and force said strip into engagement with a floor.

5. In a device of the class described, the

combination with a door hingedly connected 65 to a support, of a flexible weather strip, substantially U-shaped springs slidably connected intermediate their ends to said strip, means connecting one end of each of said springs rigidly to the bottom of said door, 70 a slideable bar connected to the other end of each of said springs, an adjustable contact member engaging said bar and adapted for engaging said support upon closing said door to distort said springs and force said strip into engagement with a floor, and independent spring means for moving said bar to normal position to withdraw said strip from engagement with the floor upon opening of said door.

6. In a device of the class described, the 75 combination with a door hingedly connected to a support, of a flexible weather strip, substantially U-shaped springs slidably connected intermediate their ends to said strip, means connecting one end of each of said 80 springs rigidly to the bottom of said door, a slideable bar connected to the other end of each of said springs, an adjustable contact member engaging said bar and adapted for 85 engaging said support upon closing said door to distort said springs and force said strip into engagement with a floor, and manually operated means for maintaining said flexible strip in engagement with a floor independent of open or closed position of the door.

7. In a device of the class described, the 90 combination with a door hingedly connected to a support, of a flexible weather strip, substantially U-shaped springs slidably connected intermediate their ends to said strip, means connecting one end of each of said 95 springs rigidly to the bottom of said door, a slideable bar connected to the other end of each of said springs, an adjustable contact member engaging said bar and adapted for 100 engaging said support upon closing said door to distort said springs and force said strip into engagement with a floor, independent 105 of open or closed position of the door, and manually operated means for maintaining said independent spring means 110 inoperative and for moving said strip into engagement with a floor, independent of 115 open or closed position thereof.

8. In a device of the class described, the 120 combination with a closure member hingedly connected to a support, of a flexible strip, resilient means connecting said strip to said closure member, means for distorting said resilient means to position said strip in a predetermined manner with respect to said closure member and including an adjustable contact member for engagement with said support upon movement of the closure mem-

ber, and adjusting means for maintaining said strip in a predetermined fixed position with respect to said closure member and independent of movement of the latter.

5 9. In a device of the class described, the combination with a closure member, of a strip, springs engaging said strip fixedly

connected at an end of each with respect to said closure member, and movable means connected to the other ends of said springs 10 for movement to distort said springs and adjustably position said strip with respect to said closure member.

HALLIE E. TRIPP.
